DESIGN FOR A BATTERY DUST COVER

Sidney B. Blakely, St. Paul, Minn., assignor to
National Battery Company, St. Paul, Minn., a
corporation of Delaware

Application February 16, 1949, Serial No. 903

Term of patent 14 years

(Cl. D26—6)

To all whom it may concern:

Be it known that I, Sidney B. Blakely, a citizen of the United States, residing at St. Paul, in the county of Ramsey and State of Minnesota, have invented a new, original, and ornamental Design for a Battery Dust Cover, of which the following is a specification, reference being had to the accompanying drawing, forming a part thereof.

In the drawing:

Figure 1 is a top plan view of a battery dust cover, showing my new design;

Fig. 2 is a side elevational view of the same, and

Figure 3 is an end elevational view thereof.

I claim:

The ornamental design for a battery dust cover, as shown.

SIDNEY B. BLAKELY.
